CLAIM

The ornamental design for a flexible container bag, as shown and described.

DESCRIPTION

FIG. 1 is a first perspective view of a flexible container bag showing our new design;

FIG. 2 is a second perspective view thereof;

FIG. 3 is a front view thereof;

FIG. 4 is a back view thereof;

FIG. 5 is a top view thereof;

FIG. 6 is a bottom view thereof;

FIG. 7 is a right view thereof;

FIG. 8 is a left view thereof;

FIG. 9 is an enlarged view thereof indicated in FIG. 1;

FIG. 10 is an enlarged view thereof indicated in FIG. 2; and, FIG. 11 is an enlarged view thereof indicated in FIG. 3.

The broken lines shown in the figures are for illustrative purposes only and form no part of the claimed design.

1 Claim, 11 Drawing Sheets
